UNITED STATES PATENT OFFICE

CLIFTON D. PETTIS, OF NEW YORK, N. Y.

BRAKE-SHOE CONSTRUCTION

Application filed October 22, 1927. Serial No. 227,941.

The present invention relates broadly to the art of brake shoes, and more particularly to brake shoes of the type having either a pressed metal shell or a metal reinforcing back cooperating with the body of the shoe for carrying or strengthening the same.

It is customary in the art to which the present invention relates to construct reinforced brake shoes of the character in which the cast-iron body or the composite body, depending upon the character of the shoe, is either reinforced or carried by a shell or reinforcing back of the proper contour and construction. With such a shoe, it is necessary to provide means for attaching the shoe in operative position for use, this usually being accomplished by the use of a so-called center lug. The present invention is concerned more especially with the construction of such center lug, whereby desirable results are obtained.

In the accompanying drawings there are shown for purposes of illustration only, certain preferred embodiments of the present invention, it being understood that the drawings do not define the limits of my invention as changes in the construction and arrangement of the parts disclosed therein may be made without departing either from the spirit of the invention or the scope of my broader claims.

In the drawings:

Figure 1 is a top plan view of reinforcing and supporting means for a brake shoe in accordance with the present invention;

Figure 2 is a side elevational view, partly broken away, of the construction shown in Figure 1;

Figure 3 is a perspective view, on an enlarged scale, of the center lug of Figures 1 and 2;

Figure 4 is a side elevational view of the center lug of Figure 3 before the ends thereof have been bent into interlocking arrangement with the reinforcing means;

Figure 5 is a view similar to Figure 4, illustrating a slightly modified embodiment of the invention;

Figure 6 is a view similar to Figures 4

and 5 showing still another form of the invention; and

Figure 7 is an end elevation of the construction shown in Figure 6.

It will be apparent to those skilled in the art that the present invention, as hereinafter described in detail, is not limited in its utility with respect to any particular type of back or reinforcing means, and that the form of shell shown herein is illustrative only. For purposes of convenience of description, and not by way of limitation, the term "reinforcing means" will be herein-after utilized as definitive of shells, special backs, reinforcing inserts and the like, in connection with which the present invention may be utilized.

In accordance with the present invention, there may be provided a reinforcing means 2 of any desired construction, provided on opposite sides of its transverse center line with transversely extending elongated slots 3, preferably entirely enclosed by the metal of the reinforcing means, and adapted for the reception of legs 4 formed in any desired manner on a center lug or key lug 5. This center or key lug, which is for the purpose of receiving a key for attaching the shoe in place for use, is conveniently formed of sheet metal bent to provide a substantially flat top 6 having an overall length preferably substantially equal to but slightly less than the width of a standard shoe, and carrying the downwardly projecting legs at its opposite ends. A center lug in accordance with the present invention, prior to being assembled in cooperative relation with the reinforcing means, will be of the form substantially as shown in Figure 4 with the legs each lying

in a plane substantially normal to the plane of the back, whereby they may be easily passed through the openings 3 in the reinforcing means. With the form of my invention illustrated in Figures 1 to 4 both inclusive, the amount of insertion of the legs is limited by providing each of them on opposite sides thereof with cut-away portions forming downwardly operative shoulders or offset bearing portions 7 adapted to abut

against the back of the reinforcing means as clearly indicated in the drawings.

After an attaching lug and reinforcing means have been assembled in the manner described, the legs are bent outwardly and upwardly into engagement with the under surface of the reinforcing means as clearly indicated in Figures 2 and 3. During the bending operation the center lug is preferably held tightly in engagement with the reinforcing means whereby the deformation of the legs will be effective for drawing the shoulders 7 into tight engagement with the back of the reinforcing means, thereby effectively closing the opposite ends of each of the slots 3 and preventing the possible escape therethrough of the cast metal or composition or special filling material, as the case may be. The bent up portions of the legs are effective for sealing the outside edges of each of the openings, and the flow of metal produced by the application of bending pressure will slightly thicken the legs adjacent the portions 8 where they extend through the reinforcing means, thereby causing the inside surface of each of the legs to tightly engage the corresponding sides of the slots. In this manner, the slots are completely closed on all of their sides against the possibility of the escape of the material constituting the main body of the shoe.

At the same time, the provision of a plurality of shoulders 7 on each of the legs insures spaced points of support effectively resisting distortion of the lugs while in use.

In order to increase the effectiveness of the bent over portions of the legs, and preclude possibility of withdrawal of an attaching lug from a finished shoe, each of the legs is preferably provided with an area of changing section at some point throughout its length to thereby provide a more or less abrupt shoulder 9 adapted to become interlocked with the filling 10 of the shoe, a portion only of which is indicated in the drawings. Such an interlocking engagement resists any tendency of the legs to straighten out while in use and thereby become disengaged from the reinforcing means.

In Figure 5, there is illustrated a slightly modified embodiment of the invention in which the legs are each provided on their opposite sides with portions of changing section to provide a shoulder 9' on opposite sides of each leg.

In some cases it may be desirable from a manufacturing or utilitarian standpoint to eliminate abrupt shoulders 7 of the character referred to and provide a leg construction similar to that shown in Fig. 6 in which the sides of each of the legs are provided with tapered portions 11 forming offset bearing portions adapted to wedge the legs tightly in position as they are assembled with the reinforcing means, it being understood that the

slots provided for the reception of the legs will be of such dimensions as to insure an operation of this character.

While the taper imparted to the legs may be relied upon to accurately position them with respect to the reinforcing means, it will, at least in some cases, be desirable to so construct the center lug as to preclude possibility of error during assembly. For this purpose each of the legs may be provided with a struck-out portion 12, as clearly shown in Figures 6 and 7, which portions are pressed out of the plane of the legs to provide shoulders 13 adapted to engage the back of the reinforcing means and definitely position the lugs with respect thereto.

With all of the forms of my invention there are provided opposed bearing points for each of the legs on opposite sides of each of the legs. This is not only effective for more adequately sealing the slots formed in the reinforcing means, but also for preventing relative movement between the parts when assembled and giving added strength thereto.

Other advantages of the invention arise from the provision of a center lug provided not only with opposed bearing points or surfaces on opposite sides of each of its legs, but also from the provision of legs of such construction as to more effectively interlock with the body of the shoe and thereby resist any tendency of the same to straighten out.

Still other advantages of the invention arise from the provision of an attaching lug of such construction that accurate positioning thereof with its top 6 in absolute parallelism with the plane of the reinforcing means is insured.

I claim:

1. As an article of manufacture, an attaching lug for brake shoes, comprising a body portion having a plurality of legs formed on each side thereof and combined bearing and movement restricting portions on opposite sides of each of said legs adapted to properly position the lug with respect to brake shoe reinforcing means.

2. As an article of manufacture, a lug comprising a top portion having legs projecting therefrom, a plurality of offset bearing portions on each of said legs, and means on each of said legs adapted to interlock with the material constituting the body of a brake shoe.

3. As an article of manufacture, an attaching lug for brake shoes comprising a top having a plurality of legs projecting from each side thereof, and opposed offset bearing surfaces on opposite sides of each of said legs.

4. As an article of manufacture, an attaching lug for brake shoes comprising a top having a plurality of legs projecting therefrom, and opposed offset bearing surfaces on opposite sides of each of said legs, said legs being cut away below said bearing portions.

to provide areas of changing section adapted to interlock with the body of a brake shoe.

5. As an article of manufacture, an attaching lug for brake shoes comprising a top having legs thereon, a tapered bearing portion on each of said legs, and means cooperating with said tapered bearing portions and facilitating the assembly of the lugs with reinforcing means.

10. As an article of manufacture, an attaching lug for brake shoes comprising a top having a plurality of legs, each of said legs having a tapered bearing surface formed thereon.

15. As an article of manufacture, an attaching lug for brake shoes comprising a top having a plurality of legs, each of said legs having a tapered bearing surface formed thereon, and also having a portion of changing 20 section below said bearing portion and adapted to interlock with the material comprising the body of the shoe.

25. As an article of manufacture, an attaching lug for brake shoes, comprising a body portion having a plurality of legs formed on each side thereof in spaced relationship, and offset bearing portions on opposite sides of each of said legs adapted to properly position the lug with respect to the brake shoe 30 reinforcing means.

35. As an article of manufacture, an attaching lug for brake shoes, comprising a body portion having a plurality of legs formed on each side thereof in spaced relationship, and offset bearing portions on opposite sides of each of said legs adapted to properly position the lug with respect to the brake shoe 40 reinforcing means, each of said legs having means thereon adapted to interlock with the material constituting the body of a brake shoe.

45. A brake shoe comprising reinforcing means provided with four slots, and a center lug shaped to provide four legs for cooperating with said slots, said legs each being formed on opposite sides thereof with offset bearing portions.

50. A brake shoe comprising reinforcing means, and a center lug having a body portion formed on each of opposite sides with a plurality of legs, each of said legs affording a plurality of points of engagement with the reinforcing means tending to resist relative movement between the reinforcing means 55 and lug in any direction, the reinforcing means being traversed by slots, one for each leg.

In testimony whereof I have hereunto set my hand.

60 CLIFTON D. PETTIS.
